UNITED STATES PATENT OFFICE.

ARTHUR E. BLUNT, OF WENDELL, IDAHO.

GATE.

1,268,427.

Specification of Letters Patent.

Patented June 4, 1918.

Application filed November 5, 1915. Serial No. 59,865.

To all whom it may concern:

Be it known that I, ARTHUR E. BLUNT, a citizen of the United States, residing at Wendell, in the county of Gooding and State 5 of Idaho, have invented certain new and useful Improvements in Gates; and I do hereby declare the following to be a full, clear, and exact description of the invention, such as will enable others skilled in the art to 10 which it appertains to make and use the same.

This invention relates to gates, and mechanism for operating the same, and the principal object of the invention is to provide 15 reliable and efficient means for unlatching a gate and for swinging it open or closed by means of a cord depending from a post within reach of a driver in a vehicle.

Another object of the invention is to provide 20 means whereby the gate may be quickly adjusted to hang properly so that the free end of the gate will not rub against the ground and be raised a sufficient distance to clear obstacles in swinging the gate.

25 The foregoing and other objects may be attained by means of the construction illustrated in the accompanying drawings, in which—

Figure 1 is a perspective view of a gate 30 made in accordance with this invention,

Fig. 2 is a horizontal sectional plan view of the same showing the gate closed,

Fig. 3 is a similar view showing the gate open,

Fig. 4 is a perspective view of the elbow 35 lever for operating the latch of the gate,

Fig. 5 is a detail sectional view and elevation of the lower hinge of the gate, and

Fig. 6 is an enlarged fragmentary view of 40 a portion of the gate and gate post showing the connection of the bell cranks 19 thereto.

Referring to the drawings, the numeral 1 designates as an entirety, a gate, provided 45 with diagonal braces 2 and 3. The top and bottom rails of the gate are separated by means of a central upright 4, and at the center of the gate and extending above the same is an upright 5. A bar or cable 6 is connected at its opposite ends to the top 50 bar of the gate, and extends through the upright 5. The top rail or bar 7 of the gate extends beyond the gate as indicated at 8. A post 9 is provided with an aperture in the upper end thereof and the rail 7 is provided 55 with a metal yoke 10 having a pin projecting from the lower side of the same into said

aperture to form a pivot for the upper end of the gate. At the lower side the gate is provided with a T-bolt 11 mounted in a bearing or support 12 connected to the post 60 9. The bearing 12 is slotted to permit the bolt 11 to move throughout a half circle.

For adjusting the gate vertically at its free end, a turn buckle 13 is connected to sections 14 and 15 of rods, the section 14 65 being connected to the curved rod or cable 6, and the section 15 being connected at 16 to a yoke or plate 17 connected to the end 8 of the extension of the upper bar 7 of the gate. Pivoted in the yoke 17 as at 8 70 are the bell crank levers 19, as clearly shown in the drawings. It will thus be seen that the free end of the gate will be braced in such a manner that the same will clear the roadway and should the gate tend to sag it 75 will be understood that such may be taken up by operating the turn buckle 13.

Connected to the oppositely disposed ends of the levers 19 are operating cords or wires 20, said cords or wires extending across the 80 top of the gate to an arm 21 supported upon a stop post 22. The cord or wire 20 passes around a pulley 23 on the arm 21. Connected to the parallel arms of the levers 19 are cords or wires 23 which are passed 85 through an eye 24 and extended along the top bar 7 of the gate. The cord or wire 23 is connected to the eye 24 and to an elbow lever 25 provided at one end with a yoke 26 pivoted at 27 to the upright 5. The other 90 end of the lever 25 is connected to the wire 23^a, and a continuation of the wire 23^a leads to a spring latch 28 connected to the free end of the gate. A keeper 29 for the spring latch 28 is secured to the gate post 30. 95

The fence post 31 is provided with a diagonal brace 32 and the fence wire 33 extends from the post to said brace.

From the foregoing it will be obvious that by turning the turn buckles 13, the gate may 100 be adjusted vertically at its free end to compensate for the weight on the gate at this end. By pulling upon either of the cords or wires 20, the spring latch 28 is first released from the keeper 29, and the gate is 105 swung to one side or the other, and the elbow lever or latch 25 engages a hook 34 on one of the posts 32 and holds the gate open. When the other cord 20 is pulled, the latch 25 is released from the hook 34 and the gate is 110 swung closed, the spring 28 riding over the keeper 29 until it is engaged therewith.

From the foregoing it will be obvious that a gate made in accordance with this invention is extremely simple in construction, is reliable and efficient in operation, and cannot readily get out of order, while simple means are provided for adjusting the gate as required.

Various changes may be made in the details of construction without departing from 10 the spirit and scope of the invention as defined in the claim.

What is claimed is:—

A gate comprising upper and lower rails, an extension formed on the rear end of the 15 upper rail, means connecting the upper and lower rails together, an upright bar secured to the central portion of the upper rail and

extending upwardly therefrom, a truss bar connected to the opposite ends of the upper rail and passing through said upright, a pivot carried by the extension, a pivot carried by the lower portion of the gate, and means for adjusting the gate including a turn-buckle and oppositely disposed rods, one of said rods being connected to the 20 upright and the other being connected to the rear end of the extension, as and for the purpose specified.

In testimony whereof I affix my signature in presence of two witnesses.

ARTHUR E. BLUNT.
